United States Patent Office

Des. 194,314
Patented Jan. 1, 1963

194,314

AUTOMOBILE

Joseph T. Cunningham, 1661 Ashton Court, Miami, Fla.

Filed Jan. 19, 1960, Ser. No. 59,100

Term of patent 14 years

(Cl. D14—3)

The dominant features of my design reside in the portions shown in full lines.

I claim:

The ornamental design of an automobile, as shown and described.
